FRANK G. STEINER, OF CHICAGO, ILLINOIS, ASSIGNOR TO STEINER SALES COMPANY,
OF SALT LAKE CITY, UTAH, A CORPORATION OF UTAH

FEED CONTROL DEVICE FOR TOWEL CABINETS

Application filed December 23, 1929. Serial No. 416,038.

In towel dispensing cabinets where a feeding instrumentality is provided for delivering the clean web of towel to the user and a take-up device is arranged to wind up the soiled portion of the towel within the cabinet, it is desirable to provide a lock device which when moved to its release position, will permit the delivery of a predetermined length of towel during the period or time that 10 elapses between the release of the feeding instrumentality and the relocking of the same, and it is further desirable to provide means to prevent the effective operation of the release mechanism until a certain time 15 has elapsed after the delivery of the towel has begun.

The particular object of this invention is to provide a time control mechanism adapted for use with a cabinet such as shown in my 20 Patent #1,724,229, issued August 13, 1929, as an improvement on or substitute for the dash pot and plunger mechanism shown and described in this patent.

Other objects of the invention will appear 25 from the following detailed description.

The invention consists generally of various constructions and combinations, all as hereininafter described, and particularly pointed out in the claims.

30 In the accompanying drawings forming a part of this specification

Figure 1 is a vertical sectional view through a towel dispensing cabinet embodying my invention;

35 Figure 2 is a detail sectional view showing the particular arrangement of the time control device in its normal position;

Figure 3 is a similar view showing the slide connected with the time device raised to a 40 point where it prevents the operation of the release mechanism;

Figure 4 is an edge view showing the connection of the slide with the feeding instrumentality;

45 Figure 5 is an outside view with the wall of the casing partially broken away, looking toward the end of the feeding instrumentality and showing the release mechanism in its normal position.

50 In the drawings, 2 represents a suitable

cabinet having a top 3, a rear wall 4, a bottom wall 5 and a suitable front door 6 that is adapted to be opened to expose the inside of the cabinet. 7 represents the inner section of the cabinet adapted to swing outwardly on pivots 8, but as this features forms no part of the present invention I do not need to describe the manner of such movement. 9 is a feed roll having a roughened peripheral surface. 10 is a similar take-up 55 roll having a driving connection with the feed roll for simultaneous movement. 11 represents a supply of clean towel resting upon a suitable support 12 within the inner section, the loose end of the towel web being 60 carried up between the feed roll 9 and the door 6 and around a pinch roll 13 that is loosely mounted in guide slots 14 in the side 65 walls of the inner casing.

The relative position of the rolls 9 and 13 is such that when a downward pull is exerted by the user on the towel web which depends through the opening in the bottom 70 of the cabinet, as plainly shown in Figure 1, the roll 13 will be drawn downwardly to

press the towel web against the roll 9 with sufficient friction so that this roll will be driven and simultaneously a corresponding movement will be imparted to the roll 10.

A take up roll 15 is mounted in guide slots 16 and the web of soiled towel is passed upwardly through the bottom of the cabinet between the wall 12 and the rear of the cabinet and in contact with a pressure device 75

17 which cooperates with the edge of the wall 12 to smooth and straighten the towel web and exert the desired degree of tension thereon so that the convolutions of the web on the roll 15 will be drawn against the roll 10 with sufficient pressure to cause the continuous 80

revolution of the roll 15 and the winding up of the soiled towel when the rolls 9 and 10 are operated. All this structure is shown and described in my former patent above referred to and is herein illustrated merely 85

to make clear the use of the cabinet.

The feed roll 9 has a bore 18 therein adapted to receive a locking bolt 19 that is free to move longitudinally within the bore a limited distance by means of an annular groove 90

20 and the pin 21. This bolt is free to slide by gravity and normally its outer end is adapted to enter a slot 22 provided in the bracket 23 and engage a stop 24 at the upper end of the slot and thereby lock the feed roll 5 against revolution. The bracket has a guideway 25 adapted to receive a slide 26 and the wall of the guideway has an opening 27 opposite the slot 22 in position to permit the end 28 of a pivoted arm 29 to be thrust through the opening 27 and contact with the end of the bolt 19 to disengage it from the stop 24. This operation of the arm 29 may be effected by means of a spring member 30 10 secured preferably to the door of the cabinet and having a cap 31 which projects outwardly in position to be pressed by the user of the towel for the purpose of initially releasing the feed roll. A cam 32 is mounted on the 20 end of the feed roll 9 and provided with a shoulder 33 in position to engage a lug 34 on the upper portion of the slide 26, whereby when the feed roll is released upon the initial movement of the bolt 19, its revolution 25 will engage the shoulder 33 with the lug 34 and raise the slide to the position indicated in Figure 3, where it will be held positively until such time as the shoulder 33 passes out of engagement with the lug 34. When this 30 occurs, the slide would naturally drop by gravity to its normal position and allow the second operation of the arm 29 and for the purpose of timing the downward movement of this slide and rendering the release arm 35 again effective, I connect a mechanism with the slide which I will now describe in detail.

A suitable plate 35 is mounted in the casing and adapted to support a train of gears. A pinion 36 is mounted on a gear wheel 37 and 40 meshes with the teeth of the gear wheel 38. The gear wheel 37 meshes with the corresponding pinion 39 that is concentric with a gear 40. An escapement lever 41 engages the teeth of the gear wheel 40 and is provided 45 with a balance wheel 42. An arm 43 is pivoted concentric with the axis of the gear 38 at one end and has its opposite end pivotally connected with the slide 26 by a rod 44. A dog 45 is pivoted on the arm 43 and is normally held by a spring 46 in engagement with the teeth of the gear 38 and a spring 47 is connected with the arm 43 and is adapted to normally exert a downward pressure on said arm that will tend to turn the gear wheels 55 and operate the escapement lever 41, the arrangement being such that when the arm 43 is raised with the slide to the position shown in Figure 3, the pressure of the spring exerting a downward force thereon, and aided by 60 gravity of the arm 43 will turn the gear 38 and through the other gears and pinions, rock the escapement lever 41 and allow the mechanism to operate with a step by step movement which will continue until the arm and 65 the slide reach their normal position as indi-

cated in Figure 2, and in such position these parts will remain until the slide is again operated and raised to a point where it will prevent the release arm from disengaging the locking bolt from its stop. 70

The wheel 42 secured to the shaft of the escapement lever operates through its weight to retard the movement or oscillations of the escapement lever. This takes the place of the ordinary small tortion spring that is 75 usually used with an escapement lever. Evidently this escapement mechanism may be so constructed that the time of the travel of the arm from its raised to its down position can be increased or decreased according to 80 the desired period of time during which the user is to be prevented from manipulating the release lever.

This escapement mechanism is comparatively inexpensive to manufacture and is extremely efficient and reliable in operation. It eliminates the use of liquid in a dash pot and the tendency of such liquid to escape from the dash pot cylinder. The escapement can be easily and quickly applied to a cabinet and being of extremely simple construction, will add but little to the initial cost. Whenever desired, the rod 44 may be disconnected and the slide used independently of the timing mechanism, in which case it will drop by 95 gravity to its normal position as soon as permitted to do so by the operating cam.

In various ways the details of construction herein shown may be modified, such as in the form shown in the escapement, and the manner of connecting it to the reciprocating slide, and still be within the scope of my invention. 100

I claim as my invention:

In a control mechanism for a towel cabinet feed releasing device, an escapement mechanism, a pivoted arm and means to bias said arm to move in one direction, a dog on said arm normally in engagement with an element of said escapement mechanism, means connecting said arm with the towel feed releasing device and means operative by a pull on the towel to store power in said arm to operate said escapement mechanism. 105

In witness whereof, I have hereunto set my hand this 18th day of December, 1929.

FRANK G. STEINER.
